UNITED STATES PATENT OFFICE.

FRITZ A. FELDKAMP, OF NEWARK, NEW JERSEY.

ACETYLENE-GAS GENERATOR.

SPECIFICATION forming part of Letters Patent No. 659,618, dated October 9, 1900.

Application filed December 4, 1897. Serial No. 660,730. (No model.)

To all whom it may concern:

Be it known that I, FRITZ A. FELDKAMP, a subject of the Emperor of Germany, residing at Newark, in the county of Essex and State 5 of New Jersey, have invented certain new and useful Improvements in Acetylene-Gas Generators; and I do hereby declare the following to be a full, clear, and exact description of the invention, such as will enable others skilled 10 in the art to which it appertains to make and use the same, reference being had to the accompanying drawings, and to letters of reference marked thereon, which form a part of this 15 specification.

The present invention has reference to a 20 novel construction of gas-generator for the production of acetylene gas.

This invention is therefore designed to provide an effective, neat, and simply-constructed 25 apparatus in which the acetylene gas is generated in proper proportion to the consumption of the gas and in which the calcium carbid in the form of powder is introduced, preferably intermittently, into the water, where it is immediately and entirely dissolved, giving off 30 only a predetermined volume of gas according to the required consumption, but the apparatus being so constructed that in case of a sudden oversupply of gas the supply of the carbid into the water is at once and automatically shut off.

Other objects of this invention not here specifically set forth will be more fully described in the accompanying specification.

The invention consists in the novel form 35 of apparatus herein described and also in the general arrangements and combinations of the several parts, all of which will be fully set forth in the accompanying specification and 40 finally embodied in the clauses of the claim.

From the specification of the invention as hereinafter set forth it will be evident that the gas-cocks of the burners in the piping connected with the apparatus can be rapidly 45 turned off and the apparatus left standing, because there is no continued generation of the acetylene gas, and as the water or the moisture therefrom owing to the present arrangement of the several parts of the apparatus can have no further effect upon the carbid, as in the constructions of apparatus now

in general use, there is no danger of explosion by an overproduction of the gas.

The invention is clearly illustrated in the accompanying drawings, in which—

55

Figure 1 is a side elevation of the apparatus embodying the principles of my present invention, and Fig. 2 is a top or plan view of the same. Fig. 3 is a longitudinal vertical section of the apparatus, clearly illustrating 60 my novel process of generating acetylene gas. Figs. 4 and 5 are a side and a top view, respectively, of a jointed or hinged lever connection for regulating the supply of the carbid into a tank containing water; and 65 Fig. 6 is a front view, and Fig. 7 a vertical section, of a link which is used in connection with the apparatus.

Similar letters of reference are employed in all of the above-described views to indicate 70 corresponding parts.

In said drawings, *a* indicates a suitable tank containing the water *b*, and *a'* is a suitable outlet-cock at or near the bottom of the tank for drawing off the lime-water formed 75 therein. Said tank is preferably provided with a funnel-shaped top *a*², terminating in a mouth *a*³, in which is secured in any well-known manner a screw-threaded tube or pipe *a*⁴, onto which is screwed a cock or valve 80 *c*, having the movable part *c'* and a nut-like portion *c*², which extends through the casing of the cock and is movable therein, as will be clearly understood; but of course any suitable form of cock or valve may be employed, 85

and said tube or pipe *a*⁴ may be dispensed with and the cock or valve secured directly over the mouth of said top *a*². Said tank *a* is also provided with an opening *a*⁵ and a valve *a*⁶, closing said opening *a*⁵, which can 90 be opened when it is desired to admit water into the tank *a*. Secured upon the top of said cock or valve *c* in any well-known manner is a receptacle *d*, having a funnel-shaped part *d*¹, terminating in an opening *d*², which 95 communicates with the said cock or valve *c*, and in the closed top *d*³ of the said receptacle *d* there may also be arranged an opening *d*⁴ and a cap *d*⁵ for normally closing said opening, but which cap can be removed for admitting the powdered calcium carbid *f* into 100 said receptacle *d*. In said closed top *d*³ there

may also be arranged a suitable cock d^6 to permit the escape of any gas that may be for some unforeseen reason in the said receptacle d . Connecting the upper part of said receptacle d with the part d' thereof near the opening d^2 is a tube d^7 , the purpose of which will be more fully described hereinafter.

E indicates a gas-receiver, comprising a suitable water tank or reservoir e , which is open at the top, as at e' , and may be provided with any desirable number of uprights e^2 , and e^3 is a vertically-moving gas-holder, open at the bottom, as at e^4 , and having a closed top e^5 , in which there may be a safety-valve e^6 and a petcock e^5 . The open part of said holder e^3 is arranged in the water g in the tank e , and on the top of said holder are a number of grooved wheels e^8 , which are in rolling contact with the uprights e^2 to properly guide the vertical movement of the gas-holder as it moves up and down by the admission or emission of the gas into the holder.

Connected with an outlet a^7 in the water-tank a is a suitable pipe h , which leads into the tank or reservoir e , at or near the bottom thereof, and terminates in an upright pipe h' above the water g in the gas-holder e^3 , substantially as represented. In that portion h^2 of the pipe h between the gas-receiver E and the water-tank a said pipe may be provided with a stop-cock h^3 for shutting off the communication between the tank a and the receiver E in case of repairs or for other reasons, and connected with a T-joint h^4 in the said pipe may be a drip-pot h^5 for catching any water caused by condensation, said pot h^5 being provided with an outlet-cock h^6 for drawing off the water from said pot when necessary. Leading from a point at or near the bottom of said water tank or reservoir e is a pipe i , which contains the burner or burners for consuming the gas. Said pipe i is provided within the receiver E with an upright pipe i' , extending above the water g and into the gas-holder e^3 , the gas in said holder passing into this pipe i' and then through the main pipe i to the burners. Said pipe i may also be provided with a shut-off cock i^2 and a T-joint i^3 , with which is connected a drip-pot i^4 for catching any condensed water that may be in said pipe i . An outlet-cock i^5 may be arranged in the lower part of said drip-pot i^4 . Secured to said vertically-moving gas-holder e^3 , preferably on the top thereof, is an arm j , to one end of which is pivotally secured, by means of a pin j' , an adjustable link l , consisting, essentially, of a pair of rods l' and l^2 , one of said rods, as l' , having a long slot or opening l^3 , whereby it can be adjustably clamped or secured in position to the rod l^2 by means of a screw l^4 , passing through said slot l^3 and working in a screw-threaded opening l^5 in the rod l^2 , as will be clearly seen from an inspection of Figs. 6 and 7. Said rod l' is provided with a hole l^6 , whereby by means of the pin j' it can be pivotally connected with the arm j . The rod l^2 is provided

with a hole l^7 , and pivotally connected thereto on a pin l^8 is a suitable lever k for controlling and operating the movable part c' of the cock or valve c , located between the water-tank a and the carbid-receptacle d . Said lever has a square hole k' for operatively connecting it with the nut portion c^2 of the cock or valve c and also has a hole k^2 for pivotally connecting it with the end of the arm l^2 , hereinabove mentioned, by means of the pin l^8 , as will be clearly evident.

The operation of the apparatus for generating the acetylene gas is as follows: Suppose the tank a and the receiver E have been properly supplied with the water to about the heights indicated in Fig. 3 of the drawings and that the receptacle d has also been filled with the finely-powdered calcium carbid and the cap d^5 again closed. Of course while filling the said receptacle d with the carbid the cock or valve c is closed, in order that there can be no generation of gas by the carbid dropping down into the water in the tank a . When the gas-holder e^3 of the receiver E has been placed in the tank or reservoir e , it rests about in the position indicated in said Fig. 3. The link connection l is now properly adjusted and connected with the lever k , so that said lever will stand at the inclination indicated in Figs. 1 and 3, and being connected with the nut portion c^2 of the cock or valve c will cause the movable part of said cock to stand open, as indicated. The finely-powdered calcium carbid now passes from the receptacle d slowly and in small quantity through the open cock or valve into the water b in the tank a , where it is at once decomposed, and the generated acetylene gas passes through the pipe h beneath the gas-holder e^3 , from which it can be withdrawn through the pipes i and i' for consumption. If the volume of gas generated in the tank a is greater than the consumption, the gas will collect in the gas-holder e^3 , which will begin to rise. At the same time the arm j causes the link l and lever k to actuate the movable part c' of the cock or valve c and by closing it at once shuts off the supply of the powdered carbid into the water in the tank a . As the gas in the gas-holder e^3 is withdrawn therefrom by consumption at the burner or burners in the pipe i the lowering of the gas-holder e^3 will again cause the link connection l and lever k to actuate the movable part c' of the cock or valve c in the opposite direction, thereby opening the said cock or valve, and a fresh supply of powdered carbid is at once admitted into the water in the tank a .

The operations of the several parts of the apparatus are so regulated that the supply of carbid into the water is intermittent and very limited, being just enough in quantity to generate the proper volume of gas as required for consumption at the burner or burners.

It will be evident that the small quantity of powdered carbid into the large quantity of water in the tank a is such that it will be im-

mediately dissolved, and there cannot be more than a predetermined volume of the acetylene gas generated, nor is it subject to moisture, as in the constructions of generators where the water is passed upon a large quantity of carbid, thus producing a sponge which continues the work of decomposition long after a further supply of gas for consumption is not needed and the gas-cocks have been 10 shut off.

Owing to the fact that there will be only a very small volume of gas generated as required there is no danger of explosion due to overcharging, nor will there be any escape of 15 the gas through the water in the receiver E.

In order that a vacuum may not be formed on the top of the powdered carbid in the receiver d as it passes through the cock c and to cause a pressure upon the carbid in order 20 that it will not clog up the valve-opening and render the apparatus inoperative, I have arranged the tube d⁷ in the manner hereinabove stated, whereby when the cock or valve c is opened enough of the gas generated in the 25 tank a will pass through said cock into the tube d⁷ and through the same upon the top of the powdered carbid in the receptacle d, whereby the said powdered carbid passes freely through the opened cock, as indicated 30 in Fig. 3.

In order that the receptacle d can be filled with a fresh supply of powdered carbid and to close the cock or valve c without raising the gas-holder e³, the lever k is preferably 35 constructed as indicated more especially in Figs. 4 and 5. In this construction the lever k comprises two arms k³ and k⁴, pivotally connected, as at k⁵, on a pin k⁶. Secured to the arm k³ on a pin or screw m is a bar n, having 40 a finger-piece n', the end of said bar being normally under a lug or projection k⁷ on the arm k⁴, whereby the two arms are rigidly connected and open and close the cock or valve c during the falling and rising of the gas- 45 holder e³; but when the bar n is disengaged from said projection k⁷ by being turned to one side then the two arms k³ and k⁴ can be moved on their pivotal connection k⁵ in the manner of a knuckle or a hinge joint, and the arm k³ 50 is employed to close the cock or valve c, as will be clearly evident, which permits of the

filling of the receptacle d without interfering with the position of the gas-holder e³ in the receiver E. When the receptacle d has been refilled with the carbid, the arms k³ and k⁴ are 55 again rigidly connected, and the link l and lever k again operate to automatically control the action of the cock or valve c as the acetylene gas is generated and consumed.

I am fully aware that many changes may 60 be made in the arrangements and combinations of the several operating mechanism, as well as in the details of the construction thereof, without departing from the scope of my present invention. Hence I do not limit 65 my invention to the exact arrangements and combinations of the parts nor to the details of the construction thereof as herein described, and illustrated in the accompanying drawings. 70

Having thus described my invention, what I claim is—

In a gas-generating apparatus, the combination, with a gas-receiver, comprising a water-tank and a water-sealed gas-holder vertically movable in said water-tank, of a water-tank a, a receptacle containing powdered carbid arranged directly above said water-tank a, pipe connections between said carbid-receptacle and said tank a, a valve or cock between said receptacle and tank a, and mechanism connected with said valve or cock and controlled by the vertically-moving gas-holder to open and close said valve or cock and the communication between said tank a and the carbid-receptacle, consisting, essentially, of an arm on said gas-holder, a lever k connected with said valve or cock, and a link connection between said arm on the gas-holder and said lever k, said lever k comprising a pair of 85 hinged arms, and means connected therewith for holding said hinged arms in a rigid position, substantially as and for the purposes set forth. 90

In testimony that I claim the invention set 95 forth above I have hereunto set my hand this 3d day of December, 1897.

FRITZ A. FELDKAMP.
